UNITED STATES PATENT OFFICE.

ALBERT THOMPSON, OF COLLINSTON, LOUISIANA.

HAMES.

1,412,322.

Specification of Letters Patent. Patented Apr. 11, 1922.

Application filed July 23, 1921. Serial No. 487,048.

To all whom it may concern:

Be it known that I, ALBERT THOMPSON, a citizen of the United States, residing at Collinston, in the county of Morehouse and 5 State of Louisiana, have invented new and useful Improvements in Hames, of which the following is a specification.

This invention relates to improvements in hames, the general object of the invention being to provide spring means for connecting the traces with the hames so as to relieve the horse of sudden strains due to the implement striking an obstruction and also to 10 make it easier for the horse or team to start 15 the load.

Another object of the invention is to provide a set of springs on each member of the hames, one spring being arranged adjacent the top and the other the bottom of the 20 member with a flexible member connecting the two springs together, with pulleys for guiding the flexible member.

This invention also consists in certain other features of construction and in the 25 combination and arrangement of the several parts, to be hereinafter fully described, illustrated in the accompanying drawings and specifically pointed out in the appended claims.

30 In describing my invention in detail, reference will be had to the accompanying drawings wherein like characters denote like or corresponding parts throughout the several views, and in which:—

35 Figure 1 is a view showing my invention applied to the hames.

Figure 2 is an enlarged face view of one member of the hames with my invention thereon.

40 Figure 3 is a section on line 3—3 of Figure 2.

Figure 4 is a section on line 4—4 of Figure 2.

Figures 5 and 6 are detail views.

45 In these views the two members of the hames are shown at 1 and their connecting means at 2. In carrying out my invention I provide a hooked projection 3 adjacent each end of each member, each projection 50 supporting a coil spring 4. A block 5 is connected with each member, the lower end of said block being closer to the lower spring than to the upper spring. This block is provided with a longitudinally extending

55 passage 6 and a guiding pulley 7 journaled in the block partly projects into the passage

adjacent the lower end thereof. An elongated opening 8 is formed in the block and a pulley 9 is adjustably arranged in said opening by having its shaft 10 arranged to engage any one of a number of sets of bearing holes 11 in the upper and lower walls of said opening. A cable 12 has its upper end connected with the lower end of the upper spring and this cable passes through the passage 6 in the block and is looped around a small pulley 13 on the upper end of the lower spring, and then the cable passes into the opening 8 over pulley 9 and out through the side of the opening 8. A hook 14 is secured 70 to the end of the cable and this hook is adapted to be engaged by the trace chain, a portion of which is shown at 15.

It will thus be seen that when the horse or team first takes the load the pull on the 75 traces will stretch the springs so as to relieve the horse or team from sudden strain. The pulleys in the block will guide the cable.

In order to prevent a sudden pull or jerk from throwing the small pulley 13 against the lower end of the block and locking it against movement I recess said lower end of the block, as at 16, to receive this pulley, the walls of the recess acting as a stop to limit the stretching movement of spring. A pin 80 17 passes through a small hole in the block into a hole in the shaft 10 of pulley 9 in order to hold said shaft in position. By adjusting the pulley 9 in the block the draft can be lowered or raised as desired. 90

It is thought from the foregoing description that the advantages and novel features of my invention will be readily apparent.

I desire it to be understood that I may make changes in the construction and in the 95 combination and arrangement of the several parts, provided that such changes fall within the scope of the appended claims.

What I claim is:—

1. A hames having upper and lower 100 springs secured to each member thereof, a cable having one end connected with the upper spring and having a part slidably engaging the lower spring, means for connecting the other end of the cable with the 105 trace and guiding pulleys for the cable.

2. A hames having upper and lower projections on each member thereof, a spring carried by each projection, a cable having its upper end connected with the upper spring 110 and having a part slidably connected with the lower spring, a block on each member

intermediate the springs having passages therein for the cable, guiding pulleys for the cable in said passages and a hook connected with the other end of the cable.

5. A hames having upper and lower projections on each member thereof, a spring connected with each projection, a pulley connected with the upper end of the lower spring, a cable having one end connected with the lower end of the upper spring and having a part looped around the pulley on

the lower spring, a block on each member intermediate the springs and having a longitudinally extending passage therein and an opening passing through one side thereof ¹⁵ through which the cable passes, guiding pulleys in said passage and opening and a hook on the other end of the cable for engaging a trace.

In testimony whereof I affix my signature. 20

ALBERT THOMPSON.
